(57) **CLAIM**

The ornamental design for an ice machine interface, as shown and described.

DESCRIPTION

FIG. 1 is a top side perspective view of an ice machine interface according to the present design in use;

FIG. 2 is an enlarged top side perspective view of the ice machine interface of FIG. 1;

FIG. 3 is a side view of the ice machine interface of FIG. 2, the cross-section taken along line 11-11 of FIG. 2; and,

FIG. 4 is a front view of the ice machine interface of FIG. 2, the cross-section taken along line 12-12 of FIG. 3.

The broken line showing is included for the purpose of illustrating and forms no part of the claimed design.

1 Claim, 4 Drawing Sheets

FIG. 1

FIG. 3

FIG. 4
